MAGAZINE SAFETY RAZOR

Joseph Muros, Cambridge, Mass., assignor to Gillette Safety Razor Company, Boston, Mass., a corporation of Delaware

Original application August 13, 1940, Serial No. 352,388. Divided and this application March 22, 1944, Serial No. 527,541

7 Claims. (Cl. 30—40)

This invention relates primarily to safety razors of the type organized to receive fresh sharp blades one by one as delivered from a magazine source of supply, although certain of its features may be usefully applied to safety razors in which the blades are supplied by hand. In one aspect the invention consists in a novel combination of safety razor and magazine in which the two are so organized that the razor receives blades substantially in shaving position directly by endwise movement from the magazine in a single continuous step. In another aspect the invention consists in a novel safety razor compact in design, convenient and efficient in use and adapted for stropping while the blade remains in the blade holder.

The extreme thinness of safety razor blades and the fragile character of their shaving edges renders these blades difficult to handle and to locate in a safety razor ready for shaving without danger of cutting the user or of impairing the keen edge of the blade by contact with the razor or the blade packing. As herein shown the magazine of my invention is shaped to contain eight or ten blades in a stack, maintaining their cutting edges out of contact with all parts of the magazine and substantially protecting the blades from exposure. The razor on its part is equipped with a blade holder designed to receive a blade directly from the magazine by endwise movement substantially in shaving position and to clamp it automatically in such position when the magazine is removed.

An important feature of my invention consists in a safety razor having a stationary head carrying fixed blade-locating devices, herein shown specifically as a pair of spaced hooks, in combination with a frame mounted to rock in the head and carrying a movably mounted blade holder to which a blade may be delivered for presentation to the blade-locating devices. A safety razor of this construction has advantages in compactness of design and economy of manufacture in that both the frame and the head may be fashioned from suitably formed blanks of sheet metal. As herein shown spring mechanism is provided for urging the frame at all times in a direction to press the holder with its blade toward stationary blade hooks. An operating arm or lever is provided for retracting the frame and through it the blade holder, thus temporarily withdrawing the edge of the blade from the blade hooks when it is desired to replace the blade in the razor. A convenient construction includes a

frame standing upright at an angle of about 45° in the head with the blade maintained by the blade hooks at substantially right angles thereto, that is to say, with a forward and downward inclination of about 45°. The frame is provided in its upper wall with an elongated tongue and this is bent forwardly and projected through a slot in the head so that it may serve both as an operating lever for rocking the head when it is desired to release a blade and also as a seat for the strop in the stropping operation and as a guide in presenting the magazine.

The magazine of my invention is provided with an element having the two functions of registering it in the proper relation to the blade holder and releasing the used blade so that a new one may be presented to the blade holder. As herein shown this element may take the form of an elongated key or arm shaped to pry the frame carrying the blade holder away from the blade hooks which are a part of the stationary head of the razor. At the same time the magazine itself is accurately aligned with the blade holder and a new blade may be advanced to replace the used blade which has been released by the action of the key.

Other features of the invention consist in giving the key a forked shape to straddle the operating lever of the frame, in providing cooperative guiding means to insure the proper path of insertion and providing cooperating cam surfaces so that the displacement of the frame and the release of the used blade may be easily brought about.

These and other features of the invention will be best understood and appreciated from the following description of a preferred embodiment thereof, selected for purposes of illustration and shown in the accompanying drawings, in which:

Figs. 1 and 2 are views of the razor head in side elevation, showing the blade holder in two different positions;

Fig. 3 is a similar view partly in section, showing a strop in position in the razor;

Fig. 4 is a fragmentary view of the razor head in front elevation;

Fig. 5 is a sectional view on the line 5—5 of Fig. 6;

Fig. 6 is a plan view of the blade holder shown on a greatly enlarged scale;

Fig. 6a is a view in perspective of the pivoted head frame as seen from above;

Fig. 7 is a plan view of the razor head as seen from above;

Fig. 8 is a view in perspective of the magazine; Figs. 9, 10 and 11 are views of the razor assembled with the magazine as seen from above, the feed slide being shown in three different positions; and

Fig. 12 is a view of the razor head in front elevation with portions broken away and showing the magazine in assembled relation.

The handle of the razor includes at its upper end a metal ferrule 10 which is detachably secured to a transverse plate or bar 11 forming the base of the razor head. The head may be formed from a sheet metal blank by suitable punching and bending operations. The bar 11 merges rearwardly into a narrow upwardly inclined flange 12 and forwardly into an upright vertical flange portion 13. The vertical flange portion 13 in turn merges into an upwardly and forwardly inclined wall 14 and this merges into an overhanging horizontal portion 15. The portion 15 is bent upwardly at its forward corners and formed into a pair of spaced blade hooks 16. Between these hooks the material of the head is bent downwardly to form a guard 17. The guard is corrugated in its upper surface and perforated so that it presents a guard bar for engaging the face of the user in advance of the blade edge. The vertical flange portion 13 of the head is provided at its opposite ends with transverse rearwardly extending ears 18 and between these ears extends a transverse fulcrum shaft 19. The stationary head of the razor thus comprises the integral sheet metal member shaped as described with the blade hooks and guard and the fulcrum shaft supported in the ears 18 thereof.

The movable part of the razor head comprises an elongated, box-shaped, sheet metal frame 23 generally rectangular in contour and in cross-section and, therefore, stiff in structure. This frame is pivotally mounted adjacent to its lower side to rock upon the fulcrum shaft 19 as an axis between the ears 18. Its end walls are carried upwardly to provide bearings, as shown in Fig. 6a, for two parallel transverse shafts 25 and 26. Its rear wall extends upwardly and is then bent forwardly, merging into a flat top wall and this in turn merges into a downwardly extending front wall, all as shown in Fig. 6a. This front wall of the movable frame is spaced slightly to the rear of the stationary front wall 14 of the razor head. The frame 13 may be rocked rearwardly by the prying action of a finger inserted between the wall 14 and the front wall of the frame, as will presently appear. The frame is constantly urged toward the left or in counter-clockwise direction about the shaft 19 by a stiff leaf spring 27 shown in Fig. 3. The forward end of this spring is received in a slot provided for that purpose in the front flange portion 13 of the razor head as shown in Fig. 4. The spring 27 passes under the shaft 19 and its rear edge engages in a notch provided for that purpose in the rear wall of the frame 23. The spring is normally curved upwardly and consequently tends to rock the frame forwardly carrying its upper end toward the stationary blade hooks 16.

Integral with the front wall of the pivoted frame 23 and at the upper edge thereof is formed a wide tongue or arm 28. This arm extends forwardly and passes with clearance through an aperture 20 provided in the forward wall 14 of the razor head. It extends downwardly and forwardly from the aperture 20 in convenient position to act as an operating arm for rocking the

frame 23 rearwardly on the shaft 19 against the tension of the spring 27. The top wall of the frame 23 is so located as to provide a seat for the strop 20 and yieldingly presses the latter upwardly against a transverse roll mounted to rotate freely on the shaft 25 between the side walls of the frame, as shown in Fig. 3. The frame 23 thus maintains yielding engagement between the roll and the strop 20 and eliminates danger of slipping between the two while it simplifies the construction of the razor by obviating the necessity of additional rolls which would otherwise be necessary. The front wall of the frame 23 is interrupted by the arm 28 which is formed in part from material thereof, as best shown in Fig. 6a.

Pivotedly mounted in the frame upon the upper transverse shaft 26 is a blade holder. This is formed of sheet metal folded to present two flat blade-engaging plates 32 and 33 connected by a resilient cylindrical hub portion which encircles the transverse shaft 26. The plate 32 is intact but the plate 33 is recessed to provide a resilient detent 34 adapted to snap into an aperture in a blade presented to the holder and thus prevent retracting movement of the blade. The shaft 26 carries at its left-hand end as shown in Figs. 9 and 12 a pinion 36 and this meshes with a corresponding pinion 35 located on the left-end of the shaft 25. This geared connection between the two shafts causes the blade holder to reverse its position in the stropping operation as is customary in safety razors of this general type.

One suitable form of blade 40 for use with the above-described razor is shown in Fig. 11. It is a narrow single-edged blade having end notches 41 and a centrally located aperture 42 with parallel edges and rounded ends. The blade 40 may be inserted in the blade holder by pushing it forcibly between the plates 32 and 33 of the holder. The plates are bevelled at their right end to facilitate presentation of the blade and the detent 34 is arranged to snap into the central aperture 42 of the blade when that has been moved into registration with the detent. When a blade is seated and held by the blade hooks 16 the blade holder is disposed substantially at right angles to the frame 23 or tangentially with respect to the axis of the frame.

It is advantageous, of course, to present the blades mechanically from a magazine. One suitable type of magazine is that disclosed and claimed in Letters Patent No. 2,312,502, dated March 2, 1943, although certain modifications are necessary in adapting that magazine for the safety razor herein disclosed. The magazine may be bent to shape from a blank of thin sheet metal or it may be moulded from any suitable thermo-plastic material. It comprises an elongated shell 44 of rectangular outline forming an enclosure of which the top is formed by longitudinally inturned flanges 45 and 46 separated by a wide centrally located slot which extends from one end to the other of the shell. The flanges 45 and 46 form a guideway for a feed slide 47 which is provided with undercut inner walls fitting these flanges. The flanges are provided at both ends with stops 48 and 49 in the shape of upturned ears which limit the path of movement of the feed slide 47.

Set in the bottom of the magazine centrally and in line with the axis of the slide between the flanges is a pair of upstanding pins 50 and

51. The pin 50 at the forward end of the magazine terminates below the plane of the inner face of the flanges by an amount equal to the thickness of one of the blades for which the magazine is designed. The end of this pin in co-operation with the flanges 45 and 46, therefore, gauges the depth of the discharge opening in the left-hand end of the magazine. The pin 51 is longer and effectively closes the rear end of the magazine. A curved leaf spring, not shown, is arranged to bear upon the lowermost blade of the blade stack and yieldingly lift the whole stack and maintain the uppermost blade in contact with the flanges 45 and 46. At its left-end the magazine is provided with a projecting arm or key 52 adapted to be inserted in the safety razor for the purpose of registering the magazine in the proper position for the presentation of a blade and of temporarily retracting the blade holder. The outer end of the arm 52 is tapered and forked, being provided with an elongated slot 53 so located as to straddle the arm 28 as suggested in Fig. 12. The arm 52 is also provided with a projecting cam rib 54 located just above the slot 53 and with a projecting hook 55 struck out of the metal of the arm. The inclined front wall 14 of the head is provided with an elongated slot 29 at its right-hand end into which the projecting hook 55 may move when the arm 52 of the magazine is inserted in operative position between the stationary forwardly inclined wall 14 of the head and the front wall of the movable frame 23. The hook 55 is in effect a guiding projection which cooperates with the top edge of the slot 29 to keep and guide the key 52 at the proper level when it is forced into the razor. Adjacent to and within the end of the slot 29 the material of the razor head is formed to present an outwardly diverging wall 21. The inner face of this wall forms in effect a cam surface which cooperates with the rib 54 when the arm 52 is inserted and is effective to pry the frame 23 rearwardly about the axis of the shaft 19 thereby retracting the blade holder and removing the edge of the blade from contact with the stationary hooks 16. The blade is thus freed so that it may be forced toward the left and out from between the plates 32 and 33 of the blade holder. It will be understood that in this movement the upper surface of the blade is not wholly disengaged from the hooks and consequently the blade holder is maintained definitely in the angular position shown in Fig. 1, but as already intimated, the sharp edge of the blade is withdrawn from the bend of the hooks 16. Thus, the old blade or the new blade, or both of them, are always effective positively to prevent angular displacement of the blade holder. The right end wall of the frame 23 is provided with a shallow notch or recess 59 as shown in Fig. 6a, to provide clearance for the arm 52 of the magazine when the arm is inserted between the stationary front wall 14 of the head and the front wall of the movable frame 23.

Assuming that the user wishes to replace the blade shown in shaving position in the razor of Fig. 7, he will insert the arm 52 of the magazine in the manner explained between the front wall of the frame 23 and the inclined wall 14 of the head until further movement is arrested by engagement of the razor frame with the bend 52' of the arm 52. In this position the frame 23 has been rocked and the blade 40 moved rearwardly from the position shown in Fig. 7 to the position shown in Fig. 9, i. e. out of edge contact with

the blade hooks 16. The feed slide 47 of the magazine is now advanced toward the left feeding with it the uppermost blade of the stack in the magazine. As the movement of the feed slide progresses the new blade is advanced between the sides of the blade holder and the old blade is progressively pushed out of the razor head as indicated in Fig. 10. Finally at the end of its movement the new blade is fully seated in the razor head and the old blade fully ejected therefrom as suggested in Fig. 11. The magazine may now be retracted whereupon the spring 27 is immediately effective to rock the frame 23 forwardly and seat the corners of the new blade within and against the blade hooks 16, thus accurately establishing the proper shaving relation between the edge of the blade and the stationary guard 17.

The frame 23 is held upright in the razor head at about an angle of 45° to the axis of the handle and the blade hooks are so located that the blade carrier makes a forward and downward angle of about 45° when the blade is fully seated in the blade hooks for shaving. When the operating lever 28 is lifted the frame and blade holder are rocked toward the right sufficiently to clear the edge of the blade from the hooks and consequently the blade holder is free to swing in the stropping operation and from one stropping position to another. The insertion of the arm 52 rocks the frame in the same direction but not sufficiently to disengage the blade from surface contact with the hooks: in other words the blade is freed so that it can be ejected but is still held with the blade holder against angular movement.

From the foregoing description it will be seen that I have provided a novel narrow-blade safety razor of compact design resulting to some degree from the fact that the two gear rolls are disposed in a line or plane making an angle to the axis of the razor handle and that the rocking frame is disposed in an inclined overhanging position. It should be noted also how the operating lever for the frame is shaped and located so that it serves several distinct functions beside that of rocking the frame.

The present application is a division of my application Serial Number 352,388, filed August 13, 1940 now Letters Patent No. 2,352,112, dated June 20, 1944, in which the safety razor of my invention is claimed.

Having thus disclosed my invention and shown one embodiment thereof in detail for illustrative purposes, I claim as new and desire to secure by Letters Patent:

1. A safety razor having a stationary head with blade hooks therein, a spring controlled frame pivotally mounted in the head and having an operating member for swinging the frame against spring pressure, said member extending transversely through the hook-supporting portion of the head, a blade holder carried by the frame, and a magazine having a forked arm arranged to be inserted between the head and frame to release a blade and shaped to straddle said operating member.

2. A safety razor having a stationary head with blade hooks therein and a spring controlled, pivotally mounted frame of substantially rectangular shape having a blade holder projecting at about 90° to the frame, in combination with a magazine having an arm for insertion between the head and frame and a delivery slot disposed at right angles to said arm, whereby the frame may be rocked to retract a blade in the holder

from edge engagement with said hooks while maintaining surface contact therewith.

3. A safety razor having a stationary head with blade hooks therein, a frame yieldingly held upright in the head and having a blade holder held substantially at right angles thereto, in combination with a magazine having means for guiding a blade in a path coinciding with the plane of the blade holder, and a projecting arm disposed in a plane at right angles to the guided blade for rocking the frame when the magazine is presented to the safety razor.

4. A safety razor having a head with stationary blade hooks, a frame mounted to rock in said head, a blade holder pivotally mounted in the frame and yieldingly maintained with a blade engaged in the blade hooks, in combination with a magazine having means for rocking the frame to release, without disengaging the blade from the blade hooks, the blade holder being thus held against angular displacement, and means for advancing a new blade into the holder while the holder is so held by the old blade therein.

5. A safety razor having a head with blade-locating means and a guiding surface, a spring controlled frame mounted to rock in said head;

an arm projecting transversely between the frame and the head and a blade holder carried by said frame, in combination with a magazine having a forked key shaped to be inserted between the head and the frame to separate them and to clear said arm and having a projection cooperating with the guiding surface of the head to control the path of the key.

6. A safety razor having a head and blade-carrying frame connected for relative yielding movement, and an operating member for separating the two, extending from the frame across the head, in combination with a magazine having a key for temporarily separating the head and frame forked to straddle said operating member.

7. A safety razor having a head with a stationary wall, a spring controlled blade-carrying frame mounted to rock in the head and having an operating arm extending transversely through an aperture in the said stationary wall of the head, in combination with a magazine having a key shaped to be inserted between the wall of the head and the frame and having an elongated slot for receiving the operating arm when so inserted.

JOSEPH MUROS.
